RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

ELECTRICAL WARP STOP MOTION.

Application filed January 6, 1928. Serial No. 244,976.

This invention relates to improvements in electrical warp stop motions and it is the general object of the invention to provide simplified means for retaining an indication 5 after it has been given by the stop motion.

In electrical warp stop motions it is customary to provide a bank of drop wires so arranged that when one of them falls it will close an electric circuit the effect of which is 10 to energize an electro-magnet to set in motion a train of mechanism which will stop the loom. During the normal running of the loom the drop wires are found to vibrate considerably due to the jarring of the loom 15 and there is no certainty that a drop wire once fallen will continue to have electric contact with the circuit and it is found that the drop wires vibrate sufficiently to break the circuit from time to time even when the 20 drop wire is supposed to be in down position. Furthermore, it is desirable to be able to stop a loom at any given point in the cycle of the pick and as the closing of the circuit due to the falling of the drop wire may occur at 25 some point in the cycle of the loom other than the desired point and as vibration of the drop wire might break the circuit at the desired point so that stopping mechanism will be rendered ineffective, it is desirable to 30 have some form of means to retain the initial indication given by the warp stop motion. It is an important object of my present invention to accomplish this result by the use of a permanent magnet which shall operate 35 to hold the armature of the electro-magnet in stopping position even though the electro-magnet should be deenergized as a result of the vibrating of the drop wires.

It is necessary that the retaining device 40 shall release the armature of the electro-magnet so that the same may be restored to normal position when the loom is again set into operation and it is a further object of my present invention so to dispose the permanent magnet and that part of the mechanism 45 controlled by the electro-magnet that the permanent magnet will be out of holding position relatively to the armature of the electro-magnet when the loom is stopped, thereby 50 releasing the armature to assume normal position.

With these and other objects in view which will appear as the description proceeds, my invention resides in the combination and ar-

rangement of parts hereinafter described and 55 set forth in the claims.

In the accompanying drawings wherein I have shown a convenient embodiment of my invention,

Fig. 1 is a vertical section of a loom having 60 my invention applied thereto, the parts being shown in running position in full lines and in position preparatory to stopping in dotted lines,

Fig. 2 is a vertical section taken on line 65 2—2 of Fig. 1, and

Fig. 3 is a view similar to a portion of Fig. 1 but with the parts moved to stopping position and with the armature of the electro-magnet moved out of effective range of the 70 permanent magnet, the electric circuit being indicated diagrammatically.

Referring to Fig. 1 I have shown a loom 10 having a warp beam 11 to supply a sheet of warp threads W which pass over a whip 75 roll 12 toward the lease rods 13 and harnesses 14. The woven cloth C may extend over the breast beam 15 to be wound up by any convenient form of take-up mechanism not shown. The shipper handle 16 is secured 80 to a shipper shaft 17 mounted for rotation in bearings 18 one of which is shown in the drawings, said bearings being held to the breast beam 15. When the shipper handle is moved to the left as shown in Fig. 1 the power will be thrown on to drive the loom by mechanism not shown, but when the shipper handle moves to the right to assume the position shown in Fig. 3 power is thrown 85 off the loom and the latter comes to rest. It 90 is not deemed necessary to give a detailed description of the shipping mechanism as this part of the loom is very well understood and it is sufficient for the purposes of my present invention to state that when shipper handle 95 16 is in the position shown in Fig. 1 the loom is operating normally and that when said shipper handle is moved to the position shown in Fig. 3 the loom will be stopped. The matter thus far described is of common 100 construction and forms no part of my present invention.

I have shown herein one form of electrical warp stop motion and have shown a single bank of drop wires 20 each of which as shown 105 in Fig. 3 has a slot 21 formed in the upper portion thereof through which extends a contact bar 22. Projecting upwardly from

said contact bar 22 is a metallic strip 23 insulated from the bar and so disposed as to engage inclined upper edge 24 of the slot 21. The drop wires 20 are supported by the warp threads W and under normal conditions there is no electrical connection between the bar 22 and the strip 23. When a drop wire falls, however, due to a fault in the corresponding warp thread, it will electrically connect the strip 23 and the bar 22, at which time current will flow from the battery P over wire 25 to the bar 22, through the upper part of the drop wire to the strip 23, from said strip 23 through wire 26 to an electro-magnet 27 which may be held in fixed position with respect to the loom by means of a bracket 28. The current will continue to flow from the electro-magnet back to battery P through wire 29. The effect of closing this circuit is to energize the magnet 27 so that the same will attract a portion of the stopping mechanism of the loom about to be described. The mechanism just described in connection with the electro-magnet is but one of several forms which may be employed and forms no particular part of my present invention, being a form which has gone into general use where electric warp stop motions are employed.

My invention relates more particularly to the mechanism for retaining the indication given by the fallen drop wire and to means for releasing said indication after the loom has been stopped. Accordingly, in carrying my invention into effect, I secure to the bottom shaft 30 in properly adjusted angular position by means of a set screw 31 a cam 32 which cooperates with a roll 33 mounted on the rear end of a lever 34. A fixed stud 35 affords pivotal support for the lever and the latter has a forwardly projecting arm 36 having a knife edge 37 which receives a periodic downward movement from the position shown in Fig. 1. The right hand end of lever 34 is heavier than the left hand end thereof so that the cam is always in driving relationship with the lever. I do not wish to be limited to the time at which the knife edge 37 is moved downwardly nor to the frequency of its motion, as the loom may be an equal geared loom wherein the shaft 30 will rotate once for every pick or it may be a so-called "two to one" loom wherein the bottom shaft rotates once every two picks of the loom.

The shipper shaft has keyed thereto a rearwardly extending arm 40 to which is pivotally connected as at 41 the upper end of an armature member 42 forward motion of which is restrained and limited by a stop 43 secured to the loom frame. The armature member is provided with a projection 44 normally located in close proximity to the electro-magnet 47 when the shipper handle is in running position or the position shown in Fig. 1. Said armature is also provided with a pair

of spaced projections 45 and 46, respectively, which are normally placed opposite the poles N and S of a permanent magnet 47 which as shown in Fig. 4 is held in fixed position by a washer 48 and bolt 49. The permanent magnet is held by the washer against a plate 50, said plate, magnet and washer all being held in position by the single bolt 49 which extends through a portion of the loom frame 10. If desired the plate 50 and washer may be of non-magnetic material so that the permanent magnet will have a maximum attractive force.

Under normal conditions the parts will be in the position shown in full lines in Fig. 1, 80 but as soon as a drop wire falls to energize electro-magnet 27 the latter will attract the projection 44 and move the armature member 42 from the full to the dotted line position shown in Fig. 1. This movement on the 85 part of the member 42 will move projections 45 and 46 near the poles N and S, respectively, of the permanent magnet and the latter will be sufficiently strong to hold said member 42 in the dotted line position shown in Fig. 1 90 even though the electro-magnet 27 should become deenergized due to the breaking of the previously traced circuit at the drop wire as a result of vibration of the latter. At the predetermined point in the cycle of the loom the 95 cam 32 will cause depression of the knife edge 37 to engage hook 60 of the armature and the latter will be moved downwardly from the position shown in dotted lines in Fig. 1 to the position shown in Fig. 3, thus causing an 100 oscillation of the shipper shaft 17 to effect stopping of the loom as previously set forth.

It will be seen from Fig. 3 that the poles N and S of the magnet are spaced a considerable distance from the projections 45 and 46, respectively, so as to be out of holding position with respect to said projections. The permanent magnet may be adjusted with respect to the projections 45 and 46 by loosening the bolt 49 and moving said magnet either 105 toward or from the armature member, this adjustment permitting a setting of the permanent magnet which will enable the same to retain the armature in the dotted line position shown in Fig. 1 but rendering said 110 magnet incapable of holding the armature member when the latter has moved to the position shown in Fig. 3. It is a difficult matter to stop the loom instantly upon movement of the shipper handle so that as a matter of 115 fact the lever 34 will receive a slight right hand movement around the stud 35 after the shipper handle assumes the position shown in Fig. 3 and this slight movement, due to the fact that the loom continues to run a 120 fraction of a pick after the power is thrown off, will be sufficient to disengage the knife edge 37 from the hook 60 on the bottom of the armature member 42. The latter will therefore be free to move by its own weight against 125

the stop 43 and as the shipper handle is pulled on to start the loom again after the warp fault has been corrected the projections 45 and 46 will move upwardly but at such a distance from the permanent magnet 47 as not to be attracted thereby.

From the foregoing it will be seen that I have provided a very simple means for retaining the indication of an electric warp stop motion so that the loom may be stopped at any predetermined point in the cycle of the pick. It will further be seen that the permanent magnet is so related to those portions of the armature member 42 which it is designed to attract that when the shipper handle moves to stopping position the permanent magnet is no longer operative to control the armature member 42 and the latter moves out of the field of influence of the permanent magnet.

Having thus described my invention it will be seen that changes and modifications may be made therein by those skilled in the art without departing from the spirit and scope 25 of the invention and I do not wish to be limited to the details herein disclosed, but what I claim is:

1. In an electrical warp stop motion for looms having a stopping member to be moved 30 to stop the loom and an electro-magnetic device to be energized whenever a fault occurs in the warp, an armature member pivotally connected to the stopping member to be moved by the electro-magnet into stopping position, a permanent magnet to hold the armature member in stopping position, and means to move the stopping member when the armature member is held in stopping position by the permanent magnet.

2. In an electrical warp stop motion for looms having a stopping member to be moved to stop the loom and an electro-magnetic device to be energized whenever a fault occurs in the warp, an armature member movable 45 with respect to the stopping member and positioned to be moved by the electro-magnet to stopping position, a permanent magnet to hold the armature member when the latter has been moved to stopping position by the electro-magnet, and means to move said armature member to cause movement of the stopping member when said armature member is held by the permanent magnet.

3. In an electrical warp stop motion for looms having a stopping member to be moved to stop the loom and an electro-magnetic device to be energized whenever a fault occurs in the warp, an armature member, a permanent magnet, said armature member being 55 normally out of range of attraction of the permanent magnet and being moved by the electro-magnet within the range of attraction of the permanent magnet to be held in stopping position by the latter, and means to move said armature member and stopping

member when the armature member is held by the permanent magnet.

4. In an electrical warp stop motion for looms having a stopping member to be moved to stop the loom and an electro-magnetic device to be energized whenever a fault occurs in the warp, a regularly moving element, an armature member connected to the stopping member and normally out of the path of the moving element, and a permanent magnet, 75 said armature member normally being out of the attractive range of the permanent magnet but being moved into the attractive range by the electro-magnet, said permanent magnet holding the armature member in the path of 80 the regularly moving element to cause the latter to impart movement to the stopping member.

5. In an electrical warp stop motion for looms having a stopping member to be moved 85 to stop the loom and an electro-magnetic device to be energized whenever a fault occurs in the warp, a regularly moving element, an armature member operatively connected to the stopping member, and a permanent magnet to hold the armature member in stopping position, said regularly moving member acting to move the armature member to move the stopping member and at the same time moving the armature member out of the range of 90 influence of the permanent magnet.

6. In a warp stop motion for a loom having a stopping member to be moved to stop the loom, an electro-magnet, a permanent magnet, an armature member common to both 100 magnets and normally out of the range of influence of the permanent magnet and operatively connected to the stopping member, means to energize the electro-magnet to attract the armature member when a fault occurs in the warp, said electro-magnet drawing the armature member into the field of influence of the permanent magnet and the latter holding said armature member, and means to act on said armature member to cause 105 movement of the stopping member when the armature member is held by the permanent magnet.

7. In a warp stop motion for a loom having a stopping member to be moved to stop the loom, an electro-magnet, a permanent magnet, an armature member common to both magnets and normally out of the range of influence of the permanent magnet and operatively connected to the stopping member, 115 means to energize the electro-magnet to attract the armature member when a fault occurs in the warp, said electro-magnet drawing the armature member into the field of influence of the permanent magnet and the latter holding said armature member, and means to act on said armature member to cause movement of the stopping member when the armature member is held by the permanent magnet, said last named means to move the 120 125 130

armature member out of the field of influence of the permanent member when moving the stopping member.

8. In a warp stop motion for a loom having a stopping member to be moved to stop the loom, an electro-magnet to be energized whenever a fault occurs in the warp, a permanent magnet, an armature member normally out of the field of influence of the permanent magnet but moved into the field of influence of the permanent magnet by the electro-magnet when the latter is energized, a regularly moving element operating at a given time in the cycle of the pick of the loom, 10 said permanent magnet holding the armature member in the path of the element so that said armature member will be engaged by the regularly moving element independently of the attraction between the electro-magnet 15 and the armature member.

9. In a warp stop motion for a loom having a stopping member to be moved to stop the loom, an electro-magnet, a permanent magnet, a regularly moving element, an armature member operatively connected to the stopping member and normally out of the path of the element, means to cause said electro-magnet to move the armature member into the path of the element whenever a fault occurs in the warp, said permanent magnet 20 acting independently of the electro-magnet to hold said armature member in the path of the element until the latter has a movement to engage said armature member to cause 25 movement of the stopping member.

10. In a warp stop motion for a loom having a stopping member to be moved to stop the loom, an armature member operatively connected to the stopping member, two magnetic members each capable of holding the armature member, said armature member normally being out of the range of influence of one of said magnets and being moved into the range of said magnetic member by the other 40

magnetic member whenever a warp fault occurs, said other magnet tending to hold the armature member independently of the first magnetic member, and means to stop the loom at a given point in the cycle of the pick of the loom when the armature member is attracted 45 by the second magnet.

11. In a warp stop motion for a loom having a stopping member to be moved to stop the loom, an armature member operatively connected to the stopping member, an electro-magnet to be energized at warp fault to attract the armature member, a permanent magnet held in fixed position, said armature normally being out of the range of influence of said permanent magnet but being moved 50 into the range of influence of said permanent magnet by the electro-magnet, and means to act on the armature member when the latter is attracted by the permanent magnet to move 55 said stopping member and also move said armature member out of the field of influence of the permanent magnet.

12. In a warp stop motion for a loom having a stopping member to be moved to stop the loom, an electro-magnet to be energized at 60 warp fault, a permanent magnet, a regularly moving element, an armature member operatively connected to a stopping member and normally out of the field of influence of the permanent magnet, said electro-magnet being 65 operative to move the armature member into the field of influence of the permanent magnet at any point in the cycle of the pick of the loom when a warp fault occurs, and said element being effective to move said armature member to stop the loom and out of the range of influence of the permanent magnet at a predetermined point in the cycle of the pick of the loom.

In testimony whereof I have hereunto affixed my signature.

RICHARD G. TURNER.
